Jack Polincovsky, New York, N. Y.

Application September 23, 1953, Serial No. 26,922

Term of patent 14 years

(Cl. D22—3)

FIG. 1

FIG. 2

FIG. 3

Figure 1 is a side elevational view of a combined knife, caliper and folding rule showing my new design as it appears with the parts thereof in open position.

Figure 2 is a view in elevation of the side opposite to that shown in Figure 1 as it appears with the parts in closed position.

Figure 3 is a top plan view of Figure 1 as it would appear with the parts in closed position.

I claim:

The ornamental design for a combined knife, caliper and folding rule, as shown.
